UNITED STATES PATENT OFFICE

JAMES D. BRUCE, OF FRAMINGHAM, MASSACHUSETTS, ASSIGNOR TO J. WALTON TUTTLE,
OF FRAMINGHAM, MASSACHUSETTS

ENVELOPE SEALER

Application filed December 30, 1930. Serial No. 505,500.

The object of this invention is to provide a simple, strong, durable and compact envelope sealer, adapted to moisten the gummed flap of an envelope preparatory to pressing it against the back of the envelope, the moistening operation being performed independently, the sealer being preferably adapted also to press the moistened flap against the envelope back by another operation.

10 Of the accompanying drawings forming a part of this specification,—

Figure 1 is a top plan view of a sealer embodying the invention.

Figure 2 is a side view of the same.

15 Figure 3 is a section on line 3—3 of Figures 1 and 2.

Figure 4 is a section on line 4—4 of Figure 1.

Figure 5 is a perspective view of the base 20 member of the sealer.

Figure 6 is a top plan view, showing the operation of moistening the envelope flap.

Figure 7 is a top plan view, showing the operation of pressing the moistened flap 25 against the envelope back.

The same reference characters indicate the same parts in all of the figures.

In the drawings, 12 designates a base which is preferably a discoidal metal plate, 13 designates an upwardly facing pad of absorbent material, such as felt or wicking, supported by the base and preferably separably secured thereto by the bearing of its margin against the undercut wall 14 of a preferably circular 35 recess 15 formed in the upper side of the base. 16 designates a liquid reservoir secured at one end to the base. The reservoir is preferably a metal tube and is preferably secured to the base by a neck 17 fixed, as by screws 40 18, to the base, and soldered or otherwise secured to an end portion of the reservoir.

To conduct water from the reservoir to the pad, I provide the base recess 15 with an extension or branch 19 (Figure 5) extending 45 under the neck 17. Said extension may be conveniently made by drilling a cavity into the upper side of the base, and part way through its thickness and breaking through the adjacent wall of the recess 15. A duct 20 formed in the wall of the reservoir and in the

neck 17, discharges water into the extension 19, the water flowing thence into contact with, and moistening the pad. To permit a sufficiently free flow of water from the reservoir, I provide an air inlet or vent 21 in the 55 under side of the reservoir above the pad. Said vent is a small hole, too small to permit a flow of water and air through it in opposite directions at the same time. It is spaced thus at a low point in the reservoir in order to be normally sealed by the water. However it permits air to enter when outflow through the duct 20 occurs. Although the vent may be located at any point in the reservoir, I prefer to place it not only at a low point in 60 order to prevent a too copious flow through the duct 20, but also over the pad, in order that any water which might issue from the vent due to shaking or agitation of the implement will be absorbed by the pad and will 65 not wet any part of the device.

A space is left between the upper side of the pad and the under side of the reservoir. No pressure is applied by means of the reservoir to the flap, but in order to furnish the 75 necessary pressure to insure sufficient moistening of the gummed area of the flap, I provide a presser in the form of a spring 25, which is secured at one of its ends to the upper side of the base near the rear end of the 80 reservoir, by a screw 26, or other suitable fastening. The presser extends from the point of attachment in a curve, or other desired location, beside the pad to the forward side of the base, and its other end is bent up 85 as shown by Figure 2, beside the reservoir to provide a throat, giving entrance to the flap.

In using the sealer the reservoir is grasped 90 between the thumb and fingers of the user and it is moved laterally over an envelope so held that its flap projects over the pad and under the reservoir with the gummed side next to the pad. This movement brings the spring retainer over the flap, causing the gummed 95 surface thereof to be pressed with a light but sufficient pressure against the upper side of the pad. After the gummed face has been thus moistened, the sealer is passed a second time over the envelope, this time on the out- 100

side of the flap, the flat and smooth under surface of the base then pressing the moistened sticky surface against the back of the envelope. The pressure thus applied may be continued and repeated as long, or as many times as the operator may consider necessary to make the union secure. Ordinarily however, two passes are sufficient to moisten and seal an envelope, and they can be performed with the utmost ease and great rapidity. The disposition of the reservoir as a handle crossing the base thereof also facilitates this method of handling.

I claim:

- 15 1. An envelope sealer comprising a base, an upwardly facing absorbent pad supported by the base, a liquid reservoir secured at one end to the base and extending across and slightly spaced from the upper face of the 20 pad, and means for conducting liquid from the reservoir to the pad, the pad being adapted to moisten the gummed flap of an envelope passed between it and the reservoir.
2. An envelope sealer comprising a base, 25 an upwardly facing absorbent pad supported by the base, a liquid reservoir secured at one end to the base and extending across and slightly spaced from the upper face of the pad, and means for conducting liquid from 30 the reservoir to the pad, the pad being adapted to moisten the gummed flap of an envelope passed over it, the base having a downwardly facing pressing face adapted to 35 press said flap against the back of the envelope.
3. An envelope sealer comprising a base having a recess and an extension therefrom in its upper side, an upwardly facing absorbent pad secured in said recess, a neck 40 fixed to and projecting upwardly from the base and covering said extension, a reservoir secured to said neck extending across and slightly spaced from the pad, the reservoir and neck being provided with a liquid 45 duct communicating with the recess extension, said duct and extension conducting liquid from the reservoir to the pad.
4. An envelope sealer comprising a base, an absorbent pad mounted on the upper side 50 of said base, a reservoir formed as a handle secured to the base and extending across the upper side thereof diametrically with a space between its under side and the pad wide enough and deep enough to place an envelope 55 with the gummed side of said flap adjacent to the pad, the reservoir and base having a duct for conducting liquid from the reservoir to the pad.

In testimony whereof I have affixed my
60 signature.

JAMES D. BRUCE.
